Inventor,

F. A. Marshall

UNITED STATES PATENT OFFICE.

E. A. MARSHALL, OF NEW YORK, N. Y., ASSIGNOR TO HIMSELF AND
THOMAS CARTER, OF SAME PLACE.

IMPROVEMENT IN TOBACCO-PIPES.

Specification forming part of Letters Patent No. **33,225**, dated September 3, 1861; antedated
August 10, 1861.

To all whom it may concern:

Be it known that I, E. A. MARSHALL, of New York city, in the county and State of New York, have invented a certain new and useful Improvement in Smoking-Pipes; and I do hereby declare the following to be a full, clear, and exact description of the same, reference being had to the annexed drawings, making a part of this specification, in which—

Figure 1 is a perspective view of the pipe with the stem drawn out. Fig. 2 is a longitudinal section of the same closed.

Similar letters of reference indicate corresponding parts in both the figures.

The object of this invention is to furnish a smoking-pipe with a stem of the ordinary length constructed in such a manner that it can be reduced, so as to be conveniently carried about in the vest or other pocket without danger of being broken or injured; and it consists in making the stem in sections and fitting them together so as to slide one within the other upon the same plan as a telescope.

To enable others skilled in the art to fully understand and construct my said invention, I will proceed to describe it.

A is the bowl of the pipe, having a short stem, B, of somewhat larger diameter than the ordinary stem of a smoking-pipe.

C is a small straight extension-tube, furnished on one end with a head, *a*, and fitted so as to slide within the short pipe-stem B, similar to the sections of a telescope, and the pipe prevented from dropping off, when held in a downward position, by a bushing, *b*, surrounding the extension-tube, and fitting snugly in the end of stem B. A bead, *c*, is fastened

on the outer end of the extension-tube, which prevents it from being pushed too far into the pipe-stem, and also furnishes something for the teeth to hold on to.

A common objection urged against all extension-pipes is that, being made in detached pieces to carry them in the pocket, they require to be taken apart and put in a box or case to prevent the stem from being lost or broken, while in a pipe of this kind no such objection can be raised, as the pipe itself forms the case for the part most liable to be broken; at the same time it is reduced to a convenient size for carrying in the pocket.

The convenience of having the pipe always ready for use without having to stop and fit one portion into the other is an advantage possessed by this pipe over all others, and this, together with the comparatively small cost at which it can be furnished, will recommend it to laborers and soldiers, for whom it is more especially designed.

It is designed, generally, to make these pipes of wood and meerschaum, although I do not confine myself to these materials, as it is evident that other materials will answer equally well.

What I claim as new, and desire to secure by Letters Patent, is—

As a new article of manufacture, a smoking-pipe made extensible by fitting one portion of the stem so as to slide within the other, as and for the purpose specified.

E. A. MARSHALL.
